NOISELESS TYPEWRITER

Lurelle V. A. Guild, New York, N. Y., assignor to
Underwood Corporation, New York, N. Y., a
corporation of Delaware

Application October 11, 1950, Serial No. 12,530

Term of patent 14 years

(Cl. D64—11)

To all whom it may concern:

Be it known that I, Lurelle V. A. Guild, a citizen of the United States, residing at New York, in the county of New York and State of New York, have invented a new, original and ornamental Design for a Noiseless Typewriter, of which the following is a specification, reference being had to the accompanying drawing, forming a part thereof.

Figure 1 is a front perspective view of a noiseless typewriter, showing my new design.

Figure 2 is a side elevational view thereof.

It is to be understood that the keyboard shown fragmentarily in broken lines is to be carried over the space adjacent thereto and provided for the same.

I claim:

The ornamental design for a noiseless typewriter, substantially as shown and described.

LURELLE V. A. GUILD.
